ABSTRACT

A lead screw apparatus is disclosed that permits fine adjustments to be made in the screw pitch. A lead screw shaft having N threads, an initial length L , and a spring constant K_1 is coaxially connecting to a spring having a spring constant K_2 substantially smaller than K_1 . By deforming the spring by a distance δ_2 , a force equal to $\delta_2 K_2$ is generated. This force is transmitted to the lead screw, producing a change in length of the screw of δ_1 where δ_1 is equal to $\delta_2 K_2 / K_1$. Since K_2 is substantially smaller than K_1 , δ_1 will be substantially smaller than δ_2 by the same order of magnitude. Thus a large change δ_2 in the length of the spring will change the pitch of the lead screw from N/L to $N/L + \delta_1$.

LEAD SCREW SHAFT WITH ADJUSTABLE PITCH

BACKGROUND OF THE INVENTION

The change of rotary motion into rectilinear or translational motion has long been accomplished by means of a lead screw and mating nut. Depending on the pitch of the screw, a specific number of revolutions of the screw will produce a known rectilinear movement of the nut. Examples of the application of such an arrangement are the movement of cutting tools along the workpiece of an automatic lathe and the so-called general purpose indexing table used by machinists to obtain x-y positioning of a workpiece.

In such applications, extreme accuracy in the fabrication of the lead screw is not necessary since the relationship between rotation of the lead screw and rectilinear movement of the engaging nut or table is not critical. However, in a field such as integrated circuit manufacture, precise positioning of a workpiece is essential. Whether we deal with the generation of a mask or printing pattern used to fabricate integrated circuits or with the process of welding the beam-lead terminals of such circuits to a supporting structure or other circuit, the precise positioning of the equipment involved is extremely critical.

In such applications where the rotation of the lead screw is expressed as θ revolutions and the movement of the mating nut or table is expressed as x microns, the tolerances permitted are such that for a range of θ from 0 to 80 revolutions, x may not vary from the theoretical solution of the equation $x = 3,500 \theta$ by more than 1.5 microns. Obviously, manufacturing precision required for the manufacture of such lead screws, even if successful, would be prohibitively expensive. Further, a change of only a few degrees between the temperature under which the lead screw was fabricated and the temperature under which it is used would completely alter the pitch accuracy.

In fabricating such screws, two distinct sources of error occur. First, there will be some departure from linearity of the x, θ curve for a given lead screw. Secondly, from one screw to another there will be some departure in the slope of the x, θ curve. Using present commercially practical tolerances with a minimal amount of selection between several screws, the precise tolerance indicated above could be met if only the first source of error were present. When combined with the second source of error however, it becomes impractical or impossible to attain the desired tolerances despite the selection of screws and fabrication to the best commercially available tolerances.

Fortunately, I have developed a lead screw mechanism having its x, θ slope readily adjustable. As a result, using commercial tolerances presently available, it is possible to adjust the pitch of an already fabricated lead screw to obtain the tolerance indicated above as being a maximum allowable deviation.

The x, θ slope is adjusted by changing the overall length of the lead screw. Since the number of threads on the screw will not change, the pitch of the screw changes as the length changes. The adjustment to the length of the screw must be precise, so directly compressing the screw would be ineffective because the compressing mechanism would then require precise adjustment.

Even assuming that such a precise adjustment were possible, once set, the mechanism's adjustment would be subject to variation due to the presence of dirt on the threads of the mechanism, vibration, movement and shock, and many other minor variables. My mechanism provides a large mechanical advantage, on the order of several magnitudes. As a result, a large change in the compressing mechanism is required to produce the precision change in the length of the lead screw (for example, the ratio between the two changes may be 10^4). Since the change in the compressing mechanism is large, any slight variation occurring in the adjustment of the compressing mechanism will have a negligible affect on the length of the lead screw. The slight variation would produce a corresponding inaccuracy in the overall length of the lead screw equal to only 10^{-4} times the slight variation in the compressing

mechanism. Even with extremely small adjustments and precision movements, an error of 1 part in 10 or 100,000 is negligible when the overall length of the lead screw is considered.

SUMMARY OF THE INVENTION

The lead screw is connected to a spring and to a member for deforming the spring and applying the force generated thereby to the screw. Since the spring constants of the spring and the lead screw differ by orders of magnitude, the change in length of the lead screw will be corresponding orders of magnitude less than the change in length of the spring. Thus a large change in spring length will produce a slight change in the length of the lead screw with a resultant precision change in the pitch of the screw. As a result, the adjustment necessary to precisely change the pitch of the screw does not require precise movement of the adjusting mechanism.

BRIEF DESCRIPTION OF THE DRAWING

FIG. 1 shows a cross-section of an embodiment of my invention in which the force applied to the lead screw is obtained by compressing the spring;

FIG. 2 shows a schematic representation of the embodiment shown in FIG. 1;

FIG. 3 shows a cross-section of an embodiment of my invention in which the force applied to the lead screw is obtained by extending the spring; and

FIG. 4 shows a schematic representation of the embodiment shown in FIG. 3.

DESCRIPTION OF THE ILLUSTRATIVE EMBODIMENTS

Referring now to FIG. 1, a lead screw 10 is shown with a mating nut or table slide 11 engaging the threads. Rotation of screw 10 will cause nut 11 to move laterally some distance, depending on the pitch of the screw and the amount of rotation. To change the distance laterally that nut 11 would move in response to a particular amount of rotation, it is necessary to alter or adjust the pitch of lead screw 10. Since the number of threads N of screw 10 is fixed, to change its pitch the overall length must be adjusted.

The mechanical apparatus shown in FIG. 1 is depicted schematically in FIG. 2. To adjust the length of screw 10 by a small distance δ_1 , it must be subjected to a force equal to δ_1 times the spring constant K_1 of the screw. This force is generated by compressing a softer spring 15 having a spring constant K_2 by a distance θ_2 . Adjusting nut 17 is threaded down on the threaded right end of rod 16. The left end of rod 16 is threaded into a fixed base 12. Since nut 17 bears on one end of spring 15, compressing the spring by a distance δ_2 will generate a force equal to $\delta_2 K_2$. Since the other end of spring 15 bears on screw 10, and since screw 10 bears against fixed base 12 at its other end, the generated force $\delta_2 K_2$ is also equal to $\delta_1 K_1$. Since spring 15 and screw 10 act in series, the total applied force F_A generated by nut 17 must equal $(K_1 S_1) [S_2 / (K_1 + K_2)]$ to produce deformations S_2 and S_1 respectively.

Thus it can be seen that a moderate compression δ_2 of a soft spring 15 having a spring constant K_2 will cause a small compression δ_1 of screw 10 which has a spring constant of K_1 . The small compression δ_1 of screw 10 due to the application of force F_A by adjusting nut 17 will cause its overall length to decrease from L to $L - \delta_1$. As a result, the pitch of screw 10 will change from N/L to $N/(L - \delta_1)$.

FIG. 3 shows an alternative mechanical arrangement which is depicted schematically in FIG. 4. In this arrangement, the spring and screw act as springs connected in parallel. By contrast, the apparatus of FIGS. 1 and 2 acted as two springs connected serially.

In the arrangement of FIGS. 3 and 4, the adjusting force F_B is generated by threading adjusting nut 39 down on rod 38. Rod 38 connects to a swiveled clamp 36 which holds the right end of spring 35. The left end of spring 35 is held by fixed base 32. The force F_B generated by extending spring 35 a distance δ_2 is equal to δ_2 times K_2 , the spring constant of spring 35.

Generated force F_B is applied through nut 39 and thrust bearing 37 to the right end of lead screw 30, which has N threads and engages a nut or table slide 31. The left end of screw 30 bears against fixed base 32. Since force F_B acts to compress screw 30 whose spring constant is K_1 , the initial length L of the screw will decrease by a small distance δ_1 . As a result the length of screw 30 will decrease from L to $L-\delta_1$, and the screw pitch will change from N/L to $N/(L-\delta_1)$.

Of course, both arrangements also permit the initial length L of screws 10 or 30 to be increased by an amount δ_1 . In FIG. 10 1, an initial tension applied to rod 16 of nut 17 could be decreased by threading nut 17 back off the rod. The length of spring 15 would then increase by a distance δ_2 resulting in a force relaxation of $\delta_2 K_2$. The length of screw 10 would increase by a distance δ_1 and its pitch will change from N/L to $N/(L+\delta_1)$.

Similarly, the adjusting nut 39 could be backed off rod 38 to relax the initial force applied to thrust bearing 37 by an amount of $\delta_2 K_2$. This would cause screw 30 to elongate by a distance δ_1 and its pitch to change from N/L to $N/(L+\delta_1)$.

It should be apparent now to those skilled in the art that other arrangements of my invention are feasible without departing from the spirit and scope of my invention. Depending on the relative change δ_1 desired in screw 10 or 30, the spring constant K_2 of spring 15 or 35, respectively, may be selected so that distance δ_2 is practical and minor variations in precision in the adjustment of distance δ_2 will have a negligible effect upon the desired adjustment of pitch of the screw.

What is claimed is:

1. A threaded member having changeable pitch comprising a first member having N threads and a spring constant K_1 ; a second member having a spring constant K_2 and located coaxial to the first member; means for changing the length of the second member by a distance δ_2 ; and means for applying to the first member the force generated by deforming the second member from its original length, so that the initial length L of the first member is selectively changed by a distance δ_1 equal to $(K_2/K_1)\delta_2$; whereby the thread pitch of the first member is changed selectively from N/L to $N/(L\pm\delta_1)$.
2. Apparatus in accordance with claim 1 wherein the second member comprises a coil spring and the changing means comprises a threaded rod and engaging nut.
3. Apparatus in accordance with claim 1 wherein the ratio K_1/K_2 is several orders of magnitude, so that the resulting ratio δ_1/δ_2 is the same orders of magnitude.
4. Apparatus for precisely adjusting the pitch of a lead screw comprising a lead screw with N threads and having a spring constant K_1 ; a spring having a spring constant K_2 ; means communicating with one end of the lead screw and with one end of the spring for producing an initial stress on the lead screw with a resulting length L ; and means for displacing the other end of the spring by a distance δ_2 and transmitting the change in stress to the lead screw, thereby causing the length of the lead screw to change by a distance δ_1 which is equal to $(K_2/K_1)\delta_2$ and the pitch of the lead screw to change from N/L to $N/(L\pm\delta_1)$.
5. Apparatus in accordance with claim 4 wherein the spring is a coil spring located coaxial with the lead screw.

65

6. Apparatus in accordance with claim 4 wherein the ratio K_1/K_2 is several orders of magnitude and the related ratio δ_1/δ_2 is the same several orders of magnitude.

7. Apparatus for precisely adjusting the pitch of a lead screw comprising

a lead screw with N threads and having a spring constant of K_1 ;

a spring having a spring constant K_2 and located so that one end of the spring communicates with one end of the lead screw; and

means communicating with the other end of the spring and with the other end of the lead screw for both producing an initial stress in the lead screw resulting in an overall length L and for deforming the spring by a distance δ_2 thereby altering the stress in the lead screw causing it to change length by a distance δ_1 equal to $[K_2/(K_2+K_1)]\delta_2$ and to change pitch from N/L to $N/(L\pm\delta_1)$.

8. Apparatus in accordance with claim 7 wherein the spring is a coil spring located coaxial with the lead screw.

9. Apparatus in accordance with claim 7 wherein the ratio K_1/K_2 is several orders of magnitude so that the resulting ratio δ_1/δ_2 is substantially the same orders of magnitude.

10. A lead screw mechanism having precisely adjustable pitch and comprising

a hollow cylindrical member having a length L , a spring constant K_1 , and N threads formed on the outer periphery thereof;

a coil spring coaxial with the cylindrical member and having a spring constant K_2 differing from K_1 by at least several orders of magnitude; and

stress producing means communicating with both the cylindrical member and the coil spring for producing a concurrent strain δ_1 in the cylindrical member δ_2 in the spring; so that the strain δ_1 produced in the cylindrical member and causing its pitch to change precisely from N/L to $N/(L\pm\delta_1)$ will result from the concurrently produced strain δ_2 several orders of magnitude greater than δ_1 and related to δ_2 substantially by the ratio K_1/K_2 .

11. Apparatus in accordance with claim 10 wherein one end of the coil spring bears against one end of the lead screw; and wherein the stress producing means includes

a base bearing against the other end of the lead screw; a rod affixed to the base and extending through the cylindrical member and the coil spring; and means bearing against the other end of the coil spring and moveably engaging the rod; so that the compressive strain in the coil spring is directly related to the compressive strain in the lead screw.

12. Apparatus in accordance with claim 10 wherein the coil spring is located within the hollow of the cylindrical member; and wherein the stress producing means includes

a base bearing against one end of the lead screw and securing one end of the spring; a threaded rod securing the other end of the spring; and an adjustable member engaging the threaded rod and bearing against the other end of the lead screw; so that the tensile strain in the coil spring is directly related to the compressive strain in the lead screw.
